[57] CLAIM

The ornamental design for a linen bag, substantially as shown and described.

DESCRIPTION

FIG. 1 is a perspective view of a linen bag showing my new design.

FIG. 2 is a rear elevational view thereof.

FIG. 3 is a top plan view thereof.

FIG. 4 is a left side elevational view thereof.

FIG. 5 is a front elevational view thereof.

FIG. 6 is a right side elevational view thereof.

FIG. 7 is a bottom plan view thereof.

FIG. 8 is a perspective view of a second embodiment of the linen bag.

FIG. 9 is a right side elevational view thereof.

FIG. 10 is a top plan view thereof.

FIG. 11 is a rear elevational view thereof.

FIG. 12 is a left side elevational view thereof.

FIG. 13 is a front elevational view thereof.

FIG. 14 is a bottom plan view thereof.

FIG. 15 is a perspective view of a third embodiment of the linen bag.

FIG. 16 is a rear elevational view thereof.

FIG. 17 is a top plan view thereof.

FIG. 18 is a left side elevational view thereof.

FIG. 19 is a front elevational view thereof.

FIG. 20 is a right side elevational view thereof.

FIG. 21 is a bottom plan view thereof.

FIG. 22 is a perspective view of a fourth embodiment of the linen bag.

FIG. 23 is a rear elevational view thereof.

FIG. 24 is a top plan view thereof.

FIG. 25 is a left side elevational view thereof.

FIG. 26 is a front elevational view thereof.

FIG. 27 is a right side elevational view thereof, and

FIG. 28 is a bottom plan view thereof.
